UNITED STATES PATENT OFFICE.

FREDERICK G. SARGENT, OF WESTFORD, MASSACHUSETTS, ASSIGNOR TO C. G. SARGENT'S SONS CORPORATION, OF GRANITEVILLE, MASSACHUSETTS, A CORPORATION OF MASSACHUSETTS.

DRIER.

1,279,165.

Specification of Letters Patent. Patented Sept. 17, 1918.

Original applications filed October 27, 1916, Serial No. 128,142, and June 4, 1917, Serial No. 172,583. Divided and this application filed December 20, 1917. Serial No. 208,169.

To all whom it may concern:

Be it known that I, FREDERICK G. SARGENT, a citizen of the United States, residing at Westford, in the county of Middlesex 5 and State of Massachusetts, have invented a new and useful Drier, of which the following is a specification.

This is a division of my applications Serial No. 128,142, filed October 27, 1916, and 10 172,583, filed June 4, 1917.

The principal objects of the invention are to provide an improved drier of the conveyer type with an improved air circulation system involving a by-pass for permitting 15 part of the air to pass around the conveyer at the side, and improvements in the construction by which the air that is brought in for drying purposes will ordinarily pass through a plurality of layers of fibrous material, but, in case any one of these layers becomes too thoroughly matted to allow the air to pass through, the by-pass will permit 20 the air to go through the rest of its course and have its full force and effect on the 25 fibrous material on any other conveyers or strands. This is important because these conditions exist usually for only short periods on account of the reciprocation of the conveyers, and yet if these by-passes are not 30 provided the whole system would be choked up during such periods and the efficiency of the machine very greatly lessened instead of only being slightly lessened as by this arrangement. Further objects and advantages 35 of the invention will appear hereinafter.

Reference is to be had to the accompanying drawings, in which—

Figure 1 is a side elevation of a drier constructed in accordance with this invention; and

Fig. 2 is a transverse sectional view on the line 2—2 of Fig. 1.

The invention is shown as applied to a 45 drier 10 having the usual blowers 11 and provided with slatted stock supports mounted on fixed transverse supporting members. This is shown in this case as horizontal. The driving mechanism need not be described in detail.

From the blowers the air circulates in the direction of the arrows shown in Fig. 2. The current is sometimes strong enough to hold the wool down on the support and pre-

vent its being fed along properly and also to 55 prevent its being exposed to the air throughout the mass of fiber.

In the form shown the drying air passes from the fans 11 inwardly, under the bottom conveyer 18 and then up through the other 60 conveyers 17 and 14 and out at the side as shown by the arrows in Fig. 2. Sometimes it happens, however, that temporarily fibrous material on one of the conveyers is matted so closely that very little air can go 65 through it. In that case with the ordinary constructions the drying action would be temporarily interrupted for all of the conveyers. In order to avoid this the following construction is provided. Brackets 50 are 70 arranged to support longitudinal rails 51 preferably formed of rolled shapes as for example, V's, these rails being stationary. On these rails are supported loose wheels 52 shaped to fit the rails. Above the wheels are 75 arranged longitudinal rails 53 of the same shape as the rails 51 but inverted and resting on the wheels. These rails 53 are provided with longitudinal bars 54 which support cross bars 55 on which pins 56 are mounted 80 that serve to reciprocate the stock. These pins move between stationary perforated slats 57 formed of sheet metal bent over at its edges to give it a dove-tail shape and fitting on similarly shaped projections 58 cutting out openings in the upper edges of the vertical flanges formed by stationary transverse irons 59. These are supported on the brackets 50. At points just inside the rolls are arranged vertical partitions 60. These 85 are spaced from the side walls of the casting and from the brackets above. They serve as wool guides and also to provide by-passes behind them that permit air to circulate around, under, behind and over them in 90 the direction of the short arrows shown in Fig. 2 at the sides of the compartments.

On account of this construction the air ordinarily would pass through in the way that has been described, but if the wool gets 100 matted on one of the conveyers, as for example, the conveyer 17, the air will pass around that conveyer and will have its full force and effect on the material on the conveyers 18 and 14. In this way two-thirds 105 of the loss due to this cause is avoided. The features of the invention are not limited to the reciprocating type of conveyer.

This invention although capable of general use is especially adapted for long fiber stock such as Southern palmetto reeds. It will be understood that the air can be caused 5 to circulate in exactly the opposite way to that shown if desired. Also the by-passes can be closed alternately on the two sides to provide a longer course for the air. For example, the upper by-passes on the left 10 and the middle one on the right can be closed.

Although I have illustrated and described only one form of the invention I am aware 15 of the fact that modifications can be made therein by any person skilled in the art without departing from the scope of the invention as expressed in the claims. Therefore I do not wish to be limited to all the 20 details of construction herein shown and described, but what I do claim is:—

1. In a drier, the combination with the drier casing, of a plurality of reciprocating conveyers therein, one over another, means 25 at the side of the casing for supporting the conveyers, and vertical partitions extending upwardly at the sides of the conveyers for the stock and to form a by-pass for air,

spaces being provided both under and over said partitions.

2. In a drier, the combination of a reciprocating conveyer, a stationary partition at each side of the conveyer to constitute a guide for the stock, said partitions being spaced from the sides of the casing, each partition being spaced from the parts above 35 it and below it to afford an air circulation and means for circulating the air up through the conveyer whereby if the conveyer is clogged the air will pass by it at 40 the sides.

3. In a drier, the combination of a reciprocating conveyer, a stationary partition at the side of the conveyer to constitute a guide for the stock, said partition being spaced from the side of the casing, and from the parts above it to afford an air circulation, and means for circulating the air freely up through the conveyer from below whereby 45 if the conveyer is clogged the air will pass 50 by it at the side.

In testimony whereof I have hereunto affixed my signature.

FREDERICK G. SARGENT.
